UNITED STATES PATENT OFFICE.

GAETANO BOSSI, OF ROME, ITALY, ASSIGNOR TO GIOVANNI MAZZACORATI, OF NEW YORK, N. Y.

RAILROAD-TIE.

No. 877,042.

Specification of Letters Patent.

Patented Jan. 21, 1908.

Application filed October 29, 1906. Serial No. 341,121.

To all whom it may concern:

Be it known that I, GAETANO BOSSI, a subject of the King of Italy, residing at Rome, Italy, have invented certain new and useful 5 Improvements in Railroad-Ties, of which the following is a specification.

My invention relates to a railroad-tie and has for its object the construction of a tie of cement or similar composition in such 10 manner as to eliminate the defects common to that kind of tie, said defects consisting principally in the difficulty of obtaining a seat for the rail which shall be rigid and at the same time sufficiently elastic as not to injure the rolling stock and cause an excessive vibration of the road.

The invention will be understood by reference to the accompanying drawings in which

20 Figure 1 is a plan view of a tie with the rails supported upon it; Fig. 2 a vertical longitudinal section on the plane of the line 2—2 of Fig. 1; Fig. 3 a transverse vertical section on the plane of the line 3—3 of Fig. 1; 25 Fig. 4 a longitudinal horizontal section on the plane of the line 4—4 of Fig. 2; Fig. 5 a horizontal section of a modified form of block; and Fig. 6 is a view of one of the sets of reinforcing rods.

30 Similar reference numerals indicate similar parts in the several views.

The tie as herein described is preferably made of cement or similar composition molded to the desired form and proportions. 35 The central body portion 1 thereof is strengthened by a longitudinal rib 2, and the end sections 3 have concave depressions 4 formed therein adapted to receive blocks 5 which constitute seats for the rails. The 40 said blocks are preferably of wood and the rails 6 are secured thereto in any usual manner. The said depressions 4 are open ended, that is they extend transversely of the tie from side to side and the side walls 45 thereof are longitudinally convergent, the blocks 5 being correspondingly formed so that said blocks will be firmly wedged in position. When laying the ties care should be observed to so place them relatively to 50 each other that the blocks 5 on contiguous ties shall have their converging walls running in opposite directions. This will prevent any displacement of the blocks as a force tending to thrust the blocks of a given 55 tie in a longitudinal direction will be resisted.

by the blocks of the contiguous tie. The depressions 4 are made slightly concave, as shown in Fig. 2 so as to leave a space between them and the bottom of blocks 5. This feature gives a certain degree of flexibility to the blocks the vibrations being transmitted to the side walls of the depressions.

Instead of making the blocks 5 of a single piece I may make them of two pieces 7, as indicated in Fig. 5, adapted to be held in position by a key or wedge 8. This permits of an easier method of adjustment for the slight differences in the dimensions of the blocks and the depressions in the ties. The 70 tie is reinforced by a series of iron rods 9 embedded in the lower part thereof and running longitudinally, and by a series of cross rods 10 in the enlarged ends 3 below the depressions 4. A second set of rods 11 extend longitudinally of the tie near the upper part thereof. The rods 11 have secured thereto, in the manner shown in Fig. 6, short rods 12 inclined upwardly and having their centers depressed to form loops which 80 surround the depressions 4 to resist lateral thrusts of the block during the passage of trains.

If necessary to replace a block 5 it is sufficient to remove the rail holding spikes, when 85 by a blow on the smaller head of the block it may be easily pushed out of the depression, the construction permitting this without the necessity of lifting the ties or disturbing the rails which they support. An additional 90 advantage is the lessening of the cost inasmuch as the rail seat or block 5 is the only part requiring renewal.

What I claim and desire to secure by Letters Patent is:—

1. A railroad tie having depressions therein extending transversely of the tie from side to side, the side walls of said depressions being longitudinally convergent, and correspondingly shaped blocks seated in said 100 depressions upon which the rails are adapted to be secured.

2. A railroad tie having depressions therein extending transversely of the tie from side to side, the side walls of said depressions being longitudinally convergent, and correspondingly shaped blocks seated in said 105 depressions to which the rails are secured, said tie being reinforced by rods embedded therein.

110

3. A railroad tie having depressions therein extending transversely of the tie from side to side, the side walls of said depressions being longitudinally convergent, and correspondingly shaped blocks seated in said depressions to which the rails are secured, said tie being reinforced by rods embedded therein, one series of said rods being bent to form loops which surround said depressions.
- 10 4. A rail - road tie having depressions formed therein and blocks seated in said de-

pressions to which the rails are secured, the bottom of said depressions being concave to provide a space below said blocks.

In testimony whereof I have hereunto 15 signed my name in the presence of two subscribing witnesses.

GAETANO BOSSI.
